DOUBLE CURTAIN OR DRAPERY ROD
BRACKET

Harry Meiners, St. Bernard, Ohio

Application May 1, 1951, Serial No. 223,948

1 Claim. (Cl. 248—263)

1

This invention relates to curtain or drapery rod brackets, and more particularly to a bracket adapted to facilitate the mounting of a pair of curtain or drapery rods.

An object of the invention is to provide a bracket which may be inexpensively fabricated from sheet material, using modern mass production techniques.

Another object of the invention is to provide a double curtain or drapery rod bracket which includes a pair of curtain or drapery rod-receptive-channels which are integral with and extend forwardly from a base or mounting panel. These channels are constructed and arranged whereby to receive the ends of a curtain or drapery rod. The bracket further includes transverse means beneath which the end portions of the rods received in the channels may be disposed for precluding accidental or unintentional relative motion about the channels, thereby securely though releasably anchoring the rods in their respective channels and to the bracket.

These and other objects may be attained by the means described herein and as disclosed in the accompanying drawings in which:

Fig. 1 is a plan view of a double curtain or drapery rod assembly embodying brackets made in accordance with the teachings of the present invention.

Fig. 2 is a front elevation of the assembly of Fig. 1.

Fig. 3 is a sectional view taken on line 3—3 of Fig. 1.

Fig. 4 is a view taken on line 4—4 of Fig. 1 but with the curtain or drapery rod removed.

Fig. 5 is a view taken on line 5—5 of Fig. 1.

Fig. 6 is a side view of the outer, channel-forming panel of a modified form of bracket comprising a detail of the present invention.

Fig. 7 is a partial front view of the bracket of Fig. 6.

Fig. 8 is a view similar to Fig. 6 illustrating a second modified form of bracket.

Fig. 9 is a partial front view of the bracket of Fig. 8.

The bracket of the present invention may be fabricated from a single piece of sheet material such as, by way of example, metal, which may be suitably formed whereby to provide a central mounting panel 10 having its opposite side edges bent forwardly thereof whereby to comprise a pair of laterally spaced panels 12 which comprise the outermost panels of a pair of opposed, complementary, laterally spaced, open-topped, U-shaped curtain or drapery-rod-receptive channels denoted generally by the numeral 20. Said

2

channels are defined by outer panels 12, bottom panels 14 and inner panels 16, as best illustrated in Figs. 4, 7 and 9. With particular reference now to Fig. 1, it will be noted that inner panels 16 are disposed in substantial spaced parallelism.

The rear ends of the bottom and inner panels, 14 and 16, respectively, preferably terminate forwardly of the central mounting panel 10, it being noted that the numeral 18 of Fig. 3 denotes the rear edge or end of bottom panel 14.

In the embodiment of the invention illustrated in Figs. 1 through 5, a transverse member 30 such as, by way of example, a rivet, bolt, pin, or the like, is secured to and spans the outer panels 12.

As best illustrated in Fig. 3, the transverse member 30 is located rearwardly of the ends of channels 20 and above its bottom panel 14 whereby to engage the upper portion of a curtain or drapery rod received within a channel 20. Transverse member 30 serves to preclude downward relative motion of the rod with reference to its channel.

Preferably a notch indicated by the numeral 32 is provided in the upper, forward portion of a curtain or drapery rod 34 wherein the dimensional characteristics of notch 32 is such as to receive transverse member 30 for thereby precluding accidental or unintentional axial shifting of the rod after having been received within its channel.

Still referring to Fig. 3, it will be observed that a curtain or drapery rod may be quickly and easily associated with my bracket by elevating the rod for introducing notch 32 under and thence upwardly onto transverse member 30. The lower edge 36 of the rod will abut against the upper face of lower panel 14, thereby completing a rod-bracket assembly.

With reference now to Figs. 6 and 7, it will be noted that an abutment 60 has been struck from the outer panel 12 to project inwardly of outer panel 12 and into the plane of channel 20, extended. The purpose and function of abutment 60 is identical with that of transverse member 30.

In Figs. 8 and 9 outer panels 12 have been provided with a different type of abutment 70 which, like 60, projects inwardly from outer panel 12 and projects into channel 20, extended rearwardly toward mounting panel 10, for engaging the forward-upper portions of a rod received in the channel.

From the foregoing, it will be noted that I have thus provided a simple, inexpensive, yet highly effective double curtain or drapery rod bracket

to which the ends of a curtain or drapery rod may be quickly and easily secured against accidental or unintentional displacement.

It should be understood that various changes and modifications in the structural details of the device may be made within the scope of the appended claim, without departing from the spirit of the invention.

What is claimed is:

A double curtain rod bracket and rod assembly 10 comprising a U-shaped body having a central web mounting portion and a pair of arms each of which arms includes outer, bottom and inner panels defining an open-topped, U-shaped curtain rod receptive channel spaced outwardly of 15 and projecting at substantially a right angle to the mounting portion, a rigidifying rod joining said outer panels at a point between said mounting portion and bottom panels and spaced from said bottom panels a distance sufficiently wide 20 to receive a curtain rod end therebetween, and a pair of curtain rods engageable between said

rigidifying rod and bottom panels and having notches in upper end edge portions thereof co-operable with said rigidifying rod for retaining the curtain rods from direct outward movement 5 relative to the bracket mounting portion, said notches in the curtain rod and portions being spaced from the ends of the curtain rods a distance substantially equal to the spacing between the rigidifying rod and the mounting portion.

HARRY MEINERS.
